UNITED STATES PATENT OFFICE.

MICHAEL B. DYOTT, OF PHILADELPHIA, PENNSYLVANIA.

LAMP-SHADE.

Specification of Letters Patent No. 12,239, dated January 16, 1855.

To all whom it may concern:

Be it known that I, MICHAEL B. DYOTT, of the city of Philadelphia and State of Pennsylvania, have invented and made a new and useful Improvement in the Construction of Shade Holders and Protectors to be Used Upon Lamps or Gas-Lights; and I do declare the following to be a full and exact description of their construction and use, referring to the annexed drawings, which form a part of this specification, in which—

Figure 1 is a vertical section of the shade holder and protector with the shade (which is also in section) placed upon it. Fig. 2 is a perspective representation of the shade holder and protector (which I shall hereafter designate by the name of shield) without the shade being placed upon it.

Similar letters of reference indicate corresponding parts in each of the several figures.

The nature of my invention and improvement consists in placing within the upper portion or neck of the shade (A) a metallic or incombustible shield (B) between which is maintained a sufficient space for the passage of air to keep the shade cool and to protect it from being burned if made of paper (which is now most generally used) or if made of metal gilded or painted, from being scorched and otherwise disfigured.

To enable those skilled in the art to make and use my invention I hereto annex a full description of the same.

The shade (A) as illustrated in the sectional drawing (Fig. 1) is made of paper, and in the usual dome form, but may be made of any other material and of any desired form, but the shield (B) must be made of metal or some incombustible material, and may correspond in form to the inside of the shade. It should be as much less in diameter than the shade as to leave a sufficient space for the free passage of air between them to keep the shade cool.

The shield should extend upward through the neck or opening of the shade, enough to protect the shade from the frame, and downward a sufficient distance to effectually guard it from the heat. There are four or more small pieces of wire (C) placed upon the outside of the shield for the purpose of holding the shade off the proper distance from the shield to admit the passing of a sufficiency of air to keep it cool. The passage of the air is indicated by the arrows in Fig. 1.

(D D) are wires attached at their upper

end to the lower edge of the shield and to a collar (F), which fits upon the gas burner (E) to support and hold the shield and shade in their proper position (G) is the flame of an ordinary gas burner and shows its relative position to the shield and shade as illustrated in Fig. 1.

Its operation is so plainly portrayed in the foregoing description that further reference to that subject is unnecessary, and its advantages are so self evident that it is scarcely necessary to name them. I will therefore simply say that by the use of the above described shade holder and shield, we are enabled to contract the opening in the top of the shade, and thus render the shade doubly effective, in reflecting downward the light, which is the principal office or intention of the shade, thus adding greatly to its utility, as well as its beauty, and as in the use of these articles it is desirable that they should be semi-transparent, in order to reflect the light and at the same time not to obscure the light unnecessarily, they are generally made of paper or some combustible material, and the places where they are most used demands considerable ornamentation and taste in their appearance, and consequent cost in their manufacture. It is therefore peculiarly desirable that some effectual means should be devised to protect them from being burned, disfigured and destroyed, which frequently happens the first time they are used, the loss of which would be sufficient to warrant the trifling additional cost of such a protector as is above described. But when it is taken in consideration that it endangers by fire a vast amount of property and lives the utility and necessity of such a protector is much more obvious, as by its use all kinds of shades may be used with perfect safety from being burned if made of combustible material and from being discolored, scorched, and disfigured, if made of metal, and for the sake of distinction, I shall call my invention the safety shade holder and protector.

What I claim as new and desire to secure by Letters Patent is—

The arrangement of the shade A, shield B and wires or their equivalents C with the intervening space, substantially as described for the protection of the shade as herein specified.

MICHAEL B. DYOTT.
